N. C. Russell, of New York, N.Y.
Letters Patent No. 1681. Dated Dec. 9th 1852.

The schedule referred to in these Letters Patent and making part of the same.

To all whom it may concern:

Be it known that I, N. C. Russell, of the City, County, and State of New York, have invented a new and original Design, the same being an Ornamentation for the Handles of Table Cutlery; and I do hereby declare that the following is a full, clear and exact description of the same, reference being had to the accompanying drawings making a part of this specification, in which,

Figures 1 and 2, are side views of a knife and fork having my design applied to them.

Figures 3 and 4, are edge views of the same.

Figures 5 and 6, sections of the same taken in the lines x, x, Figures 1 and 2. Similar letters of reference indicate corresponding parts in the several Figures. This invention has for its object the ornamenting of the handles of plain or low priced cutlery which are not provided with bolsters and which have hitherto had a very plain and comparatively common appearance, lacking the finish and neatness of the bolster knives and forks.

A represents the handle, of both the knife and fork of rectangular form in its transverse section, and B, B, are metal plates of semi-circular form which are attached to the inner end of the handle, one at each side. These plates B, B, are let into the handle, so that their outer surfaces will be flush with the external surfaces.

of the handle, and form a neat finish.

The semi-circular edges of the plates B.B. are downward, the straight upper edges being flush with the inner edges of the handle.

These plates give a finish to the handle adding greatly to its appearance and compensate for the omission of the bolster which in cutlery of a superior class is formed at the inner part of the blade of the knife or tang of the fork, adjoining the handle, and gives a finish and neat appearance to the article.

The ordinary or low-peiced cutlery having no bolsters are very plain in appearance and have a very common look, which my invention fully obviates.

Having thus described my invention, what I claim as new and desire to secure by Letters Patent is,

The configuration and application of the plates B. to the handles of table cutlery to form a new and original ornamentation or design for the same, as set forth.
